UNITED STATES PATENT OFFICE.

RUDOLPH BECKER, OF ROSELLE PARK, NEW JERSEY, ASSIGNOR TO THE SINGER
MANUFACTURING COMPANY, A CORPORATION OF NEW JERSEY.

WORK-HOLDER.

1,350,290.

Specification of Letters Patent. Patented Aug. 24, 1920.

Application filed September 6, 1918. Serial No. 252,939.

To all whom it may concern:

Be it known that I, RUDOLPH BECKER, a citizen of the United States, residing at Roselle Park, in the county of Union and 5 State of New Jersey, have invented certain new and useful Improvements in Work-Holders, of which the following is a specification, reference being had therein to the accompanying drawings.

10 This invention relates to an improvement in means for sewing the bows of hat ribbons to a hat.

The objects of the invention are, to provide a work-holding means by which the 15 edge of the upper or outer limb of a ribbon bow may be deflected to one side, while the lower limb is held and stitched to the hat, which means may be readily moved out of the way when desired and automatically held 20 in inoperative position, to provide a plurality of such means, one or all of which may be used as desired, to provide a guide or gage for coöperation with the deflecting means, and to provide shiftable means on the work- 25 arm in connection with the work holding means and guide for properly locating the work.

The invention comprises a work-holder including a work-support movable on the 30 work-arm of the machine, said work-support having an elongated needle aperture, work-gripping and detaining means adjacent said aperture, a pivotally mounted work-guide and gage adjustable toward and from said 35 aperture, an overhanging pivotally mounted arm carried by the work-support and yieldingly pressed toward the same, and independently movable work-clamping and deflecting fingers carried by said arm, said 40 fingers when in operative position extending toward the work-support adjacent the stitching point. Means are provided for holding the fingers in either operative or inoperative position. A shiftable extension is provided 45 on the work-arm for coöperation with the work-holder in the sewing operation. The work-holder is given a lengthwise reciprocating movement by suitable means, such as that shown by patent to C. M. Hor- 50 ton, No. 1,051,998, dated February 4, 1913.

Referring to the accompanying drawings, Figure 1 is a side view of a sewing machine with the work-holder attached. Fig. 2 is a horizontal section taken above the 55 work-arm. Fig. 3 is a perspective view of

the work-deflecting fingers and their support, and Fig. 4 is a sectional view on a line between the deflecting fingers.

In the drawings 1 represents the base of a machine, from which projects a work-arm 2 and an over-hanging arm 3, the latter arm carrying a reciprocating needle-bar 4 and needle 5. The work-holder comprises a work-support formed of the plates 6 and 7 secured together and slidable in a groove in the top of the work-arm. Near the front end of the work-support an elongated needle aperture 8 is provided, and adjacent said aperture short projecting work-gripping points 9 are located. The outer portion of plate 6 is slightly inclined upwardly and outwardly. A work-guide and gage is pivotally mounted on the work-support by the screw 10, which screw also serves to secure a spring-finger 11 adapted to engage a recess 12 in the work-support when the guide is in operative position. The guide is formed in two parts 13 and 14, the part 14 being slidable in dovetail grooves formed at the edges of the part 13, and the two parts being secured in adjusted position by a screw 15 passing through a slot 16 in the part 14 and threaded into the part 13. The end of the part 14 nearest the needle-aperture is turned up as at 17 to form an outwardly inclined work-guide and gage. 85 An upright 18 is secured to the plate 7 and carries an extension 19 at the top of which an arm 20 is pivotally mounted at 19'. A coiled spring 20' surrounds the pivot of the arm and has one end secured in any desired manner to the extension 19 and the other end bearing against the top of arm 20, thereby yieldingly pressing said arm downwardly. The arm 20 passes through a slot in the head of the over-hanging arm 3 90 and at its forward end carries a downwardly directed extension 21 (Fig. 3) having an overhanging flange 22 at its upper end. Mounted to slide in the head of arm 3 is a rod 23 having a collar 24 secured thereon which engages beneath the flange 22 of arm 20. A second collar 25 is secured to the upper end of rod 23, and a lever 26 fulcrumed on the arm 3 has a forked end 27 95 engaging beneath the collar 25. Connected to the opposite end of lever 26 is a link 28 leading to a pedal or other operating means. Secured to the lower end of extension 21 is a horizontal arm 29 having downwardly directed lugs 30, said arm together 100 105

with the extension 21 and arm 20 forming a pivotally mounted frame. Between the lugs 30 the arm 29 has a recess in which the needle-bar and needle move.

- 5 Pivottally connected to adjacent sides of the lugs 30 are inwardly curved fingers 31 having out-turned ends 32. At the end adjacent its pivot each finger 31 has one rounded corner 33 and one squared corner 34 (Fig. 10 4). The rounded corner permits the finger 31 to be swung up in one direction into a horizontal position, but movement upward in the opposite direction is prevented by engagement of the corner 34 with the arm 29.
- 15 Flat springs 35 are secured to the arm 29 and the free end of each spring is adapted to engage one side or the other of a corresponding corner 34, dependent upon whether the finger 31 is in a vertical or horizontal position, to thereby yieldingly hold the finger in either position. A vertical rod 36 projects upwardly from the rear end of the work-holder, and reciprocating movement is imparted to said rod and to the work-holder 20 by a cam-wheel 37 in a well-known manner, and as shown by Patent No. 1,051,998, before mentioned. A shiftable extension 38 of the work-support having a slightly inclined surface is pivotally mounted on the 25 end of the work-arm at 39, and is held in operative position by a sliding latch 40. The inner edge of the extension 38 is recessed at 41 to permit reciprocation of the work-support. The inclined surface of the extension 33 38 co-operates with the inclined surface at the end of plate 6 and the inclined guide 17 to hold the hat slightly tilted, whereby the 40 stitches may be placed close to the junction of the hat crown and rim.
- 45 In operation the fingers 31 are raised against the pressure of spring 20' by operation of lever 26 either manually or through the link 28, and the work placed in position, the guide or gage 17 having been properly 50 adjusted. The fingers 31 are inserted beneath the edge of the upper limb of the ribbon bow, and the lever 26 is released, whereupon the work is held between the projecting points 9 and the fingers 31 with the upper limb of the ribbon bow deflected. Upon 55 reciprocation of the work-holder during the stitching operation the lower limb of the bow is stitched to the hat. If it be desired to use either of the fingers 31 alone, the other one may be pushed up into the position shown in Fig. 3, where it is yieldingly retained by the spring 35.

Having thus set forth the nature of the invention, what I claim herein is—

- 60 1. In a sewing machine, stitch-forming mechanism, and a work-holder intermittently movable with respect thereto, said work-holder having opposed means for clamping a portion of the work adjacent the 65 stitch-forming mechanism, one of which

forms a deflector for holding another portion of the work away from the stitch-forming mechanism.

2. In a sewing machine, stitch-forming mechanism, and a work-deflecting finger 70 mounted adjacent thereto, for holding a portion of the work away from the stitch-forming mechanism, said finger being pivotally movable and also bodily movable longitudinally and laterally. 75

3. In a sewing machine, stitch-forming mechanism including a needle, opposed work-clamping and work-gripping means disposed adjacent thereto, one of which forms a deflector for holding a portion of 80 the work to one side of the needle-path, and means for causing a relative jogging movement between said needle and said opposed means.

4. In a sewing machine, stitch-forming 85 mechanism, work-gripping means, movable work-clamping-and-deflecting means disposed in opposition to said work-gripping means, means for holding said work-clamping-and-deflecting means in either operative 90 or inoperative position, and means for moving both said means relatively to said stitch-forming mechanism.

5. In a sewing machine, stitch-forming mechanism, a work-holder having movable 95 means for clamping a portion of the work adjacent the stitch-forming mechanism and for deflecting another portion of the work, and means for holding said first means in either operative or inoperative position. 100

6. In a sewing machine, a reciprocating needle, work-clamping and deflecting fingers movably mounted adjacent said needle, means for yieldingly holding said fingers in either operative or inoperative position, 105 work-gripping means disposed opposite said fingers, and means for yieldingly urging said fingers toward said gripping means.

7. In a sewing machine, a reciprocating needle, a work-deflector mounted adjacent 110 said needle and movable into and out of operative position, means for holding said deflector in either position, means for moving said deflector toward and from the work, and means for causing a relative lateral 115 movement between said deflector and needle.

8. In a sewing machine, stitch-forming mechanism, a plurality of work-clamping-and-deflecting means adapted to clamp one portion of the work and hold another portion away from the stitch-forming mechanism, said means being independently movable at will into operative relation with said stitch-forming mechanism, and means for moving said clamping and deflecting means 125 in unison in a plurality of directions.

9. A work-holder for sewing machines comprising a work-support provided with work-gripping means, work-clamping-and-deflecting means disposed opposite said grip- 130

- ping means, means yieldingly urging together said clamping - and - deflecting and gripping means, and manual means for separating the latter.
- 5 10. A work-holder for sewing machines comprising work-gripping means, a plurality of work-deflecting means yieldingly held in opposed relation thereto, and yielding means for holding one or more of said work-10 deflecting means out of operative position at will.
11. In combination with a sewing machine having stitch-forming mechanism, a work-holder comprising a movably mounted frame adjacent said stitch-forming mechanism, a finger pivotally mounted on said frame and having a free end adapted to deflect the work, and a spring mounted on said frame adapted to engage a side or end of said finger to thereby hold the same in work-deflecting and in inoperative position.
12. In a sewing machine, a work-arm, stitch-forming mechanism, a movable work-support carried by said arm and having projecting work-gripping means and gaging means, yieldingly held work-clamping-and-deflecting means disposed in opposition to said gripping means, and manual means for separating said clamping - and - deflecting means and gripping means.
13. In a sewing machine, a reciprocating needle, a pivotally mounted frame adjacent said needle, work-deflecting fingers pivotally mounted therein, means for independently holding said fingers in operative and inoperative position, work-sustaining and gripping means opposed to said fingers, means for yieldingly urging said frame toward said work-gripping means, and means for moving said frame and gripping means laterally with respect to the needle.
14. A work-holder for sewing machines comprising a work-support, work-gripping means thereon, an adjustable guide and gage pivotally supported on said work-support, yielding means for retaining said guide in operative position, and work-clamping-and-deflecting means opposed to said gripping means.
15. A work-holder for sewing machines comprising a work-support, opposed work-gripping and work-clamping-and deflecting means carried by said support, a guide and gage mounted on said support at one side of said means, said guide and gage being ad-justable toward and from said means and also laterally shiftable, and means for yieldingly resisting said shifting.
16. In a sewing machine, stitch-forming mechanism, a work-holder having opposed work-gripping and work-clamping-and-deflecting means adjacent said stitch-forming mechanism, an adjustable inclined guide at one side of said stitch-forming mechanism, an inclined shiftable extension for said work-support on the opposite side of said stitch-forming mechanism, and means for securing said extension in operative position.
17. In a sewing machine, stitch-forming mechanism, a work-support, means carried by said support for gripping the work and deflecting a part of the same, a guide at one side of said stitch-forming mechanism having an upwardly and outwardly inclined edge, and an upwardly inclined shiftable extension for said work-support at the opposite side of said stitch-forming mechanism.
18. In a sewing machine, a work-arm, a reciprocating needle, a reciprocating work-support on said arm having an upwardly inclined outer end with a needle-aperture therein, a shiftable extension on said arm having an inclined surface forming a substantial continuation of said inclined outer end and also having a clearance recess for said end and an upwardly inclined guide on said support at the opposite side of said needle from said extension.
19. In a sewing machine, stitch-forming mechanism, a work-support, a coöperating inclined guide and inclined work-support extension for positioning the work, and means carried by the work-support for gripping the work and deflecting a part thereof away from the stitch-forming mechanism.
20. In a sewing machine, stitch-forming mechanism, a work-arm, a reciprocating work-support carried thereby having an upwardly inclined outer end, a coöperating upwardly inclined extension for said support pivotally mounted on said work-arm, a latch for securing said extension in operative position, and means adjacent said stitch-forming mechanism for gripping a part of the work and deflecting another part away from the stitch-forming mechanism.

In testimony whereof I have signed my name to this specification.

RUDOLPH BECKER.
